CLAIM

The ornamental design for a fiber splice cassette, as shown and described.

DESCRIPTION

FIG. 1 is a perspective view illustrating a fiber splice cassette;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines in the drawings depict portions of the fiber splice cassette that form no part of the claimed design.

1 Claim, 5 Drawing Sheets
